SLUG-TRIMMING KNIFE FOR LINE CASTING MACHINES

Herman R. Freund, Brooklyn, N. Y., assignor to Intertype Corporation, Brooklyn, N. Y., a corporation of New York

Application April 4, 1951, Serial No. 219,275

4 Claims. (Cl. 199—59)

1

This invention relates to improvements in typographical slug casting machines of the general organization disclosed in U. S. Letters Patent No. 436,532, granted September 16, 1890, and particularly to slug side-trimming mechanism for such machines.

Machines of this class are generally designed to cast, in fixed molds from molten metal, slugs bearing lines of type and having trim-ribs on one side thereof to permit the trimming of the side faces of the slugs as they are being ejected from a mold between a pair of parallel knives such as disclosed in U. S. Letters Patent No. 1,202,720, granted October 24, 1916.

To assure a proper break-away and ejection of a slug from molds of the class referred to, the slug body and also the ribs thereon are ordinarily cast with a taper from the character-bearing face or top (as viewed in Figs. 3-7) toward the opposite face or bottom of the slug. Because of this taper, the bottom of a slug immediately after the break-away during ejection, becomes free to move laterally within the mold and subsequently, as ejection continues, is drawn to one side of the mold by the action of the trim-knife that trims the ribs of the slug, thus causing the slug thickness to taper from top to bottom.

In view of the standard practice of assembling slugs in a form and locking them therein it is obvious that the ideal trimming operation is one which results in a slug whose thickness across the trimmed ribs is the same at the bottom as at the top. This parallelism is particularly important when assembling long columns of small point size slugs in a make-up form such as for newspaper advertisements wherein it may readily be seen that any degree of taper toward the bottom will be multiplied many times and may consequently cause the entire column to be snapped out of the form during lock-up and completely disarranged. To overcome this difficulty, prior to the present invention, the general practice has been to insert strips of paper between slugs to compensate for the taper thereof—a tedious, annoying, and time-wasting operation.

In view of the foregoing, a principal object of the present invention is to provide a mechanism for producing slugs which, after passing between the trimming knives, will have substantially the same thickness across the trim-ribs at the top and bottom of the slug and which mechanism does not require any alteration of the mold.

To accomplish this objective I alter the opposing faces of the side-trim knives—the usual right-hand knife being provided with a small flat

2

portion extending from its cutting edge away from the mold and in a plane parallel to the casting face of the body of the mold. The left-hand knife is modified in such manner as to provide a cam surface thereon extending into the path of the slug and located at such a distance from the cutting edge of the knife as to engage the leading edge of a slug during ejection and shortly before it leaves the mold. Thus, as the slug continues to be ejected, its leading edge is shifted to the right by the cam surface, thereby inducing a counter-clockwise rotation, as viewed from above, of the slug about the "flat" adjacent the cutting edge of the right-hand knife. Since the slug is being constantly driven forwardly this rotary motion causes the rear or bottom of the slug to veer to the left away from the right-hand knife which then trims the remainder of the trim-ribs to the desired dimensions.

20 Other objects and structural details will be apparent from the following description when read in conjunction with the accompanying drawings wherein:

Fig. 1 is a fragmentary, sectional, plan view of 25 a conventional arrangement of ejector, mold, and adjustable side-trim knives.

Fig. 2 is a fragmentary, sectional, plan view on 30 an enlarged scale, showing a slug partially ejected between a pair of conventional side-trim knives and shows the bottom of a slug drawn to the right in the mold under the influence of the right-hand knife.

Fig. 3 is an end elevational view of a slug trimmed by conventional knives and tapering toward 35 the bottom.

Fig. 4 is a fragmentary, end elevational view of 40 a group of tapered slugs trimmed by conventional means and illustrates their relation to each other before being compressed in a make-up form.

Fig. 5 is a view similar to Fig. 4 but illustrating 45 the bowed effect which results when tapered slugs are compressed in a make-up form.

Fig. 6 is an end elevational view of a slug trimmed by means embodying the present invention 50 and shows adjacent to the bottom of the slug, a laterally projecting portion of one of the ribs which serves to equalize the slug thickness at the top and bottom thereof.

Fig. 7 is a view similar to Fig. 5, but illustrating 55 the inter-relationship, under compression in a make-up form, of a group of slugs trimmed by means embodying the present invention.

Fig. 8 is a fragmentary top plan view of a slug being ejected between the knives of the present 55 invention and illustrates how the usual tapering

cut is being effected before the leading edge of the slug contacts the cam surface of the present invention.

Fig. 9 is a view similar to Fig. 8 but illustrating how a counter-clockwise rotation is imparted to a slug as it engages and passes the cam surface of the present invention.

Fig. 10 is a view similar to Fig. 9 but illustrating how, during the last portion of the trimming operation, the depth of cut has been restored to the desired value.

Fig. 11 is an enlarged fragmentary view illustrating the flat pivotal portion adjacent to the cutting edge of the right-hand knife.

Referring to the drawings, Fig. 1 shows a conventional form of type-slug casting mold, an ejector blade, and a pair of side trim knives. The mold, including the usual body portion 1 and cap portion 2, contains a slug 3 and is shown in ejecting position whereat the slug is positioned to be forced out of the mold by an ejector blade 4 and hence between a pair of side-trimming knives 5 and 6.

As shown in Fig. 2, which is an enlargement of a portion of Fig. 1, the casting face 7 of mold body 1 is perpendicular to the front face of the mold whereas the casting face 8 of cap 2 is tapered towards the rear to provide a diverging passage to facilitate ejection. The trim-rib grooves 9 in cap 2 also taper toward the rear, for the same reason, but at a lesser angle. Because of this taper the slug, immediately after the ejection operation has started, is free to move sidewise and under the influence of cutting edge 11 of right-hand knife 6 it is drawn against the mold cap 2 thus producing a tapered slug 3 as shown in Fig. 3.

As may be seen in Fig. 4 a plurality of tapered slugs assembled in a chase, the floor of which is schematically represented at 12, will abut only at their upper edges whereas there are spaces between the lower edges which spaces must have filler strips inserted therein or the column will assume the bowed condition shown in Fig. 5.

A preferred way of utilizing the present invention to avoid this undesirable result is illustrated in Figs. 8, 9, 10 and 11. Referring to these figures, the right-hand knife 13 is provided with a cutting edge 14 and differs from the conventional structure in that the clearance angle of surface 15 has been increased and a narrow flat surface 16 (Fig. 11) has been provided adjacent to the cutting edge 14, the flat surface 16 being disposed in a plane parallel to that of the casting face 7 of the mold body 1 when it is in ejecting position. As shown in Fig. 8 the left-hand knife 17 of the present structure is disposed relative to the mold in the conventional manner; that is, its cutting edge 18 is aligned with casting face 7 of mold body 1 and its clearance surface 19 is disposed at the same angle as before. However, surface 19 is interrupted by an acclimate cam surface 21 extending the length of the knife and into the path of the slug travel approximately .005", after which the normal clearance angle is resumed. Cam surface 21 is disposed such a distance from cutting edge 18 that it will engage the character-bearing leading edge of a slug 22 while a small portion of the slug is still within the mold cavity 24.

As ejection continues the leading edge of the slug rides up on cam surface 21 (Fig. 9) and a counter-clockwise rotation is imparted to slug 22 about the flat 16 (Fig. 11) thus causing the left-hand face of the slug to be returned into con-

tact with the casting face 7 of mold body 1. During the final stage of the ejection of slug 22 from the mold cavity 24 the remaining portion 25 (Fig. 10) of trim-ribs 23 will be trimmed to full depth thus providing an equal thickness at the bottom of the slug and at the top.

While there is above described but one embodiment of the invention, it is possible to produce still other embodiments without departure from the inventive concept above disclosed, and it is, therefore, desired that only such limitations shall be imposed on the appended claims as are stated therein, or required by the prior art.

I claim:

1. A slug-trimming mechanism for line casting machines comprising a pair of trimming knives defining a diverging type-slug ejection path therebetween, one of said knives having an inclined shoulder extending into said path and adapted to engage the leading end portion of a type-slug passing therethrough to deflect said leading portion toward said other knife, said shoulder being located beyond the cutting edges of said knives in the direction of movement of said type-slug and being so spaced with respect to the cutting edges of said knives that the leading end portion of said slug is deflected by said shoulder before the trailing end of said slug reaches said cutting edges whereby the leading and trailing end portions of the trimmed slug are of substantially equal thickness.

2. A slug-trimming mechanism for line casting machines comprising a pair of trimming knives having confronting surfaces defining a generally diverging type-slug ejection path therebetween and having cutting edges at the entrance to said path that are spaced a predetermined distance apart, a path-defining surface of one of said knives being provided with a slug-deflecting projection adapted to engage the leading end of a slug moving along said path to urge it toward the other of said knives, the path-defining surface of said other knife having a portion adjacent to the cutting edge of said other knife that is substantially parallel to the central plane of said path, the distance between said projection and the cutting edge of said one knife being less than the length of one slug, whereby deflection of the leading end of a type-slug by said projection rotates said slug about the cutting edge of said other knife to produce a trimmed slug having leading and trailing end portions of substantially equal thickness.

3. A slug-trimming mechanism for line casting machines comprising in combination, a mold, a pair of oppositely disposed trimming knives adjacent to said mold and defining a diverging slug ejection path, ejecting means adapted to eject a type-slug from said mold between said knives, and camming means formed on the body of one of said knives adapted to deflect a type-slug during its passage between said knives, said camming means being located beyond the cutting edges of said knives in the direction of movement of said type-slug and being positioned to rotate said slug about the cutting edge of the other of said knives to produce a slug having substantially the same body thickness at its leading and trailing end portions.

4. In a slug-trimming mechanism for line casting machines, a pair of oppositely disposed trimming knives defining a diverging slug ejection path therebetween, ejection means adapted to force a type-slug past the cutting edges of said knives along said ejection path, and type-slug

deflecting means formed on the body of one of said knives at a point beyond the cutting edges of said knives in the direction of movement of said type-slug, said deflecting means being positioned to cant a type-slug during its passage between said knives to reduce the amount that the other of said knives trims the trailing end portion of said slug and thereby produce a type-slug having the same thickness at its leading and trailing end portions.
